SWITCH HOUSING

Rudolf Popp, Valparaiso, Ind., assignor to McGill
Manufacturing Company, Inc., Valparaiso, Ind.,
a corporation of Indiana

Application June 8, 1950, Serial No. 166,894

8 Claims. (Cl. 200—168)

1 The present invention relates to electric switches.

More particularly, the invention relates to electric switches having separable housings, and to the construction of such housings.

In the manufacture of electric switches, it is often convenient to construct the switch in two separable parts; the switch mechanism proper, and the housing for the switch mechanism. If the advantages of constructing switches in this manner, are to be fully availed, it is essential that the switch mechanism be easily mounted within its housing. In order that proper operation of the switch be assured, the housing must firmly seat the switch mechanism, and prevent any rattling movement of the mechanism relative to the housing. To provide maximum utility, the housing should facilitate installation of the switch in places which have limited space available for the switch, or which are not readily accessible. Along this same line, the housing should be such as to make the switch easily adapted for use in installations where the operating conditions might be such as to deleteriously affect the operation of the switch, or where the number of switching operations to be performed vary. Further, in addition to all of the above requirements, it is of course necessary that the switch be easily and cheaply manufactured.

It is therefore one object of the present invention to provide a novel electric switch housing which greatly simplifies the mounting of a separable switch mechanism therein.

Another object of the invention is to provide a separable housing for an electric switch mechanism in which the switch mechanism is firmly retained in place upon being inserted therein.

Still another object of the invention is to provide a compact electric switch housing that is particularly adapted for use in installations where the space available for the switch is limited, or not readily accessible.

A further object of the invention is to provide a separable housing for an electric switch mechanism, which is easily adapted for use in installations having widely different operating conditions, and having varying numbers of lead-in conductors to accommodate.

A still further object of the invention is to provide a housing for an electric switch, which can be easily and cheaply manufactured on a quantity basis.

A feature of the invention is the provision of a novel electric switch housing including a half oval-shaped body member formed by a pair of

2 half oval-shaped parallel plate portions joined together by U-shaped strip portion, the portions together defining a cavity having an opening in one of its sides for receiving a switch mechanism, and the housing further including a detachable covering for the opening in the body member.

Another feature of the invention is the provision of an electric switch housing including a body member having a relatively deep switch-receiving-cavity with one end open to provide access to the cavity for the introduction of a preassembled switch which has an operating member that can be projected through an opening in the end opposite to the open end, and a covering for the open end with the covering comprising a plate having a plurality of lead-in conductor accommodating notches cut in its edges, and a resilient strip secured to the plate which forms a snap-catch engaging means for attaching the covering to the body member.

A further feature of the invention is the provision of an electric switch housing comprising a body member having a switch receiving cavity with an open side providing access to the cavity, and a detachable covering for sealably closing the opening to provide a moistureproof switch housing; the covering being made of a flexible material, and having a number of frangible areas which are adapted to provide a plurality of self sealing passages for accommodating lead-in conductors to a switch contained within the housing.

Other objects, features and many of the attendant advantages of this invention will be appreciated readily as the same becomes understood by reference to the following detailed description, when considered in connection with the accompanying drawings, wherein:

Fig. 1 is a perspective view of a multi-purpose, electric switch and switch housing constructed in accordance with the present invention;

Fig. 2 is a sectional view of the switch mechanism and housing shown in Fig. 1;

Fig. 3 is a perspective view of the disassembled switch housing comprising a part of the present invention;

Fig. 4 is a perspective view of two elements comprising one part of the two-piece housing shown in Fig. 3 and comprising a part of the invention;

Fig. 5 is a perspective view of a multi-purpose switch and switch housing comprising a second embodiment of the invention;

Fig. 6 is a sectional view of the switch and switch housing illustrated in Fig. 5; and

Fig. 7 is a perspective view of the cover mem-

ber of the switch housing shown in Fig. 5, and also comprises a part of the invention.

In practicing the invention, an electrical switch having a switch mechanism contained within a separable insulating housing, is provided. The housing includes a half oval-shaped body member formed by a pair of half oval-shaped parallel plate portions having their curved edges joined by a U-shaped strip portion, and defining a cavity having one of its sides open for receiving the switch mechanism. The housing also includes a covering for the body member which, in one embodiment of the invention, comprises a plate having a plurality of notches cut in its edges for accommodating the lead-in conductors to the switch mechanism. In another embodiment of the invention presented, the covering for the body member of the housing comprises a flexible rubber cover or cap having a plurality of apertures therein for accommodating the lead-in conductors to the switch mechanism. In this last mentioned embodiment, the rubber cap sealably closes the opening in the body member, thereby keeping out moisture, dirt and other undesired matter which would injure the switch mechanism.

Referring now to the drawings more particularly, Fig. 1 shows a half oval-shaped electric switch housing having a switch actuating lever 2 extending therefrom for operating a multi-purpose switch mechanism of any well known type, such as that described in U. S. Patent No. 2,209,104, issued to Rudolf Popp and Marvin C. Carlson. The details of the construction of the switch mechanism do not form a part of this invention, and therefore have not been shown; however, the general configuration of a preassembled switch mechanism for which the housing has been particularly designed, is shown in Fig. 2 of the drawings. Broadly, the switch mechanism comprises a universally acting switching lever 2 linked to the rotary switch contacts of the mechanism held in place by a cylindrical chassis 3 that also mounts the stationary contacts of the switch, the ends of which are indicated by clips 4, to which a plurality of lead-in conductors 5 are connected. The mechanism is contained within a generally half oval-shaped body member 8 having an outwardly accessible switch mechanism receiving cavity therein, and a covering 9 therefor. Half oval-shaped member 8 is formed by a pair of half oval-shaped parallel plate portions 10 and 11 having the curved portion of the periphery thereof, joined together by a U-shaped strip portion 12. The half oval-shaped body member 8 may be an integral body of molded construction, or, if desired, may be built up from separately machined pieces. It is preferably constructed of an insulating material, but, could also be constructed of brass or the like and provided with an insulated lining. As is best seen in Fig. 2, U-shaped strip portion 12 has an aperture 13 formed in the vertex portion thereof, which accommodates the switch actuating lever 2 of the switch mechanism. By reason of this construction, the assembling of the switch mechanism is greatly facilitated. All that is required in order to properly seat the mechanism in member 8, is that the switching lever 2 be aligned somewhat with aperture 13, and the switch mechanism thrust into the member. This requires but a minimum of time and effort, and reduces the overall cost of the switch. After being inserted within member 8, the switch mechanism is retained firmly in place, and is prevented from rattling around with the member

because of its half-oval configuration. This results in preventing damage to the switch mechanism during shipping and handling, and assures proper operation of the switch. Other advantages provided by this construction will become apparent from the succeeding paragraphs.

In the embodiment of the invention shown in Fig. 1, the covering 9 comprises a rectangular plate of insulating material having a plurality of lead-in wire accommodating notches cut in two opposing edges thereof, and a resilient strip 14 secured thereto. As best shown in Fig. 3, cover plate 9 is designed to fit in a seat formed on the open end of member 8 by the ends of parallel plate portions 10 and 11, and bordered by the ends of the leg portions of U-shaped strip portion 12. Each of the ends of the said leg portions has a depression 12a or 12b formed in the outer face thereof in which a centrally disposed snap-catch protrusion 15 is positioned, and an indentation 12c or 12d formed in the end thereof for accommodating resilient strip 14. As is best illustrated in Fig. 4 of the drawings, strip 14 is secured to plate 9 by means of a pair of punched out ears 14a that project through a pair of slits 9b cut in plate 9, and, as is best seen in Fig. 2, are bent over to securely hold strip 14 to plate 9. Adverting again to Fig. 3, strip 14 is generally rectangular shaped, and is of greater length than plate 9. The portion of strip 14 extending beyond each of the edges of plate 9 has a hole 14b punched therein, and is bent toward the other, to an angle of approximately 90° with plate 9, in a clamping fashion. The cover plate thus formed is designed to fit into the seat defined by the ends of plates 10 and 11, and the ends of the leg portions of U-shaped strip 12, with the clamped end portions of strip 14, passing through indentations 12c and 12d, extending into depressions 12a and 12b, and cooperating with snap-catch protrusion 15 on each of the leg portions to operate as a snap-catch securing means. Because each of the indentations 12a and 12b are sufficiently wide to accommodate strip 14, and because plate 9 is designed to exactly fit between the ends of the legs of U-shaped strip 12, the entire housing, when assembled, forms a compact body presenting a smooth outer surface.

As has been previously pointed out, when assembling the switch mechanism within the housing, the switch mechanism is inserted in member 8 after covering 9 has been removed, with the switch actuating lever 2 protruding through aperture 13. Due to the fact that notches 9a are accessible from the side of cover plate 9, this operation can be performed after lead-in conductors 5 have been secured to the switch mechanism; thereby greatly facilitating installation of the switch. Lead-in conductors 5 are then bunched and positioned so as to fit within notches 9a, and the plate 9 fitted over the end of half oval-shaped member 8. To secure plate 9 to said member the clamps formed by the ends of resilient strip 14 are pushed along depressions 12a and 12b formed in the outer faces of each of the leg portions of U-shaped strip 12, until the holes 14b snap over protrusions 15. In this manner, installation of the switch mechanism within a compact, insulating housing is completed in a few simple operations. By making notches 9a sufficiently large to accommodate any desired number of lead-in conductors up to three or four, the housing can be used with a great variety of switch mechanisms having vary-

ing numbers of lead-in conductors, without requiring any alteration of the housing structure whatsoever.

Having completed the above operations, the assembled switch can then be mounted, as in one type of installation illustrated in Fig. 2, by means of a mounting nut 16 and a threaded neck 17 through which switch actuating lever 2 passes, on a wall or other supporting structure 18. Preferably, threaded neck 17 is secured to switch 10 chassis 3 by means of posts 19 so that upon the mounting nut 16 being drawn up, the switch mechanism is drawn against the quasi-cylindrical seat formed in half oval-shaped member 8 and is prevented from rattling around therewithin. This action also results in drawing the housing against supporting structure 18, and securing the switch firmly in position. Thus, it is apparent that the configuration of the switch housing further simplifies the installation of the switch mechanism in places wherein the space available for the switch is limited, or not readily available.

In the embodiment of the invention shown in Fig. 1, rectangular cover plate 9 can be formed by a simple punching operation. The simplicity of manufacture of cover plate 9, is made possible wholly through the nature of the opening of half oval-shaped member 8 providing a passage for insertion of a switch mechanism within the member. This type of opening renders the housing adaptable for many uses, merely by modifying the construction of the covering 9. One such modification is illustrated in Fig. 5 of the drawings. Adverting to Fig. 5, an electric switch is shown which includes a half oval-shaped body member 8 identical in construction to the body member 8 of Figs. 1, 2 and 3, and a covering 22 for body member 8. As is best shown in Fig. 6, a multipurpose switch mechanism is seated in member 8 which is identical in construction to the mechanism shown in Fig. 2, and has a switch actuating lever 2 protruding therefrom. In this embodiment of the invention, however, the covering 22 constitutes a flexible rubber covering for sealing the opening to half oval-shaped member 8, thereby providing a moistureproof, electric switch housing.

Referring to Fig. 7, the covering 9 comprises a rectangular box made of flexible rubber and having a pair of relatively thick, opposing side walls 23 and 24, integral with an equally thick bottom 26, and a pair of opposing end walls 27 and 28 closing the structure. Bottom 26 has a plurality of cup-shaped indentations 29 therein which form a plurality of thin, frangible areas 50 adapted to be punctured to accommodate the switch mechanism lead-in conductors. Prior to assembly of the switch mechanism in member 8, a number of the frangible areas equal to the number of lead-in conductors to be accommodated, are punctured, and the lead-in conductors 5 threaded therethrough. Due to the resiliency of the frangible areas, a self seal passageway for each of the lead-in conductors, is thereby provided. The conductors are then connected to the switch mechanism, and inserted in the aforementioned manner. Covering 22 is then secured over the opening in half oval-shaped body member 8.

Covering 22 is retained on member 8 by the gripping action of the wall portions 23, 24, 27 and 28, and by the coaction of a pair of cleats 32 and 33 formed on the inside of end walls 27 and 28, with protrusions 15. Cleats 32 and 33 are sufficiently wide to close depressions 12a and 12b, 70 75

and together with the wall portions 23, 24, 27 and 28, serves to prevent the passage of air into the member 8. This sealing action is further improved by the gripping action of the fractured, frangible areas 31 on each of the lead-in conductors 5. Thus, upon the member 8 and the switch mechanism being drawn up tightly against the supporting structure 18 (by mounting nut 16), the housing is tightly sealed against the entrance of moisture, dirt, or other matter, and deterioration of the switch mechanism is prevented. If desired, the depressions 12a and 12b, and protrusion 15 could be omitted when constructing body member 8, and the rubber covering 22 secured thereto by means of its gripping action only. Such modification of the housing construction is thought to be so obvious, as not to require elaboration.

From the preceding discussion, it can be seen that the invention provides a novel switch housing that greatly simplifies the assembling operation required to mount the switch mechanism within the housing. The housing is so shaped that when the switch mechanism is once seated therein, it is retained firmly in place and is prevented from rattling around within the housing. The compact form and configuration of the housing, facilitates its installation in places wherein the space provided for the switch is limited, or not readily accessible. In a particular embodiment of the invention, the switch mechanism can be connected to the lead-in conductors thereof prior to assembly of the switch mechanism within the housing; thereby further facilitating installation of the switch. Additionally, this last mentioned embodiment can be used with a variety of switch mechanisms having varying numbers of lead-in conductors, without requiring additional alterations to the housing structure. In another embodiment of the invention, a moistureproof switch housing is provided by merely modifying the construction of covering for the body member thereof. Thus, it is seen that the novel housing can be easily adapted for use in many different installations, with very little attendant trouble or expense. The half oval-shaped body member 2 may be cast in a mold, or, if desired, machined out of flat pieces of insulating material, and built up to the proper shape. By either means the manufacture of the body member is easily accomplished at a minimum cost. In either embodiment of the housing, covering 9 or 22 can likewise be constructed at a minimum cost. Thus, the novel housing can be easily and cheaply manufactured on a quantity basis. Due to the fact that in preferred construction, the housing is made of an insulating material, protection against short circuiting the switch mechanism is assured; and for the same reason, safety from the existence of any fire hazard due to bare or open electrical terminals, is provided.

From the above teachings, it is apparent that the present invention incorporates all of the features of an ideal switch housing, and that many modifications and variations thereof are obviously possible. It is therefore to be understood that such modifications are within the full intended scope of the invention as set forth by the appended claims.

I claim:

1. A switch housing comprising a half oval-shaped body member having a pair of half oval-shaped parallel plate portions and a U-shaped strip portion bent to conform to the curvature of said plate portions, said portions forming a cavity

having an open end and being sufficiently large to accommodate a switch mechanism therein, said U-shaped strip portion having an aperture in the vertex portion thereof and central depressions formed in the outer faces of the ends of each of the leg portions thereof, a snap-catch protrusion formed on the extreme end of each of said leg portions and centrally disposed within each of said depressions, and a detachable covering plate for said opening, said plate having a plurality of lead-in conductor accommodating notches cut therein and a resilient strip secured thereto, said strip having two end portions overlapping opposing sides of said plate, said end portions having centrally disposed holes formed therein and being bent to form a clasp so that said holes coact with protrusions on said body member as a snap-catch securing means.

2. An electric switch housing comprising a half oval-shaped body member having a pair of half oval-shaped parallel plate portions and a U-shaped strip portion bent to conform to the curvature of said plate portions, said portions defining an open cavity for receiving a preassembled switch mechanism therein, said cavity being sufficiently large to accommodate a preconnected switch mechanism, said U-shaped strip having an aperture in the vertex portion thereof, a snap-catch means formed on the extreme end of each of the leg portions of said U-shaped strip, and a flat cover plate for the open end of said cavity, said cover plate having a plurality of lead-in conductor accommodating notches cut therein and a resilient strip secured thereto, said strip having the two end portions overlapping opposing sides of said plate, said end portions having snap-catch means thereon and being bent so that said last-mentioned snap-catch means coact with the snap-catch means on said member to hold said member and said plate in assembled relation.

3. An electric switch housing comprising a half oval-shaped insulating body member having a pair of half oval-shaped parallel plate portions and a U-shaped strip portion bent to conform to the curvature of said plate portions, said portions defining a switch retaining cavity therein, with said cavity having an opening sufficiently large to accommodate a preconnected switch mechanism, said U-shaped strip having an aperture in the vertex portion thereof, said U-shaped strip portion having depressions formed therein at the extreme end of each of the leg portions thereof, a snap-catch protrusion centrally disposed within each of said depressions, and an insulating cover for said opening including a plate having a plurality of lead-in conductor accommodating notches cut therein and a resilient strip having overlapping ends secured thereto, said overlapping ends having holes punched therein and being bent to engage said depressions in a clamping fashion so that said holes coact with said protrusions as a snap-catch securing means.

4. An electric switch including in combination a multi-terminal, preassembled switch mechanism having a switch actuating means protruding therefrom and adaptable for use with installations requiring different numbers of switching operations, and an insulating housing for said mechanism, said housing comprising a half oval-shaped member having a pair of half oval-shaped parallel plate portions and a U-shaped strip portion bent to conform to the curvature of said plate portions, said portions defining an open cavity therein for receiving said switch mechanism, said U-shaped strip having an aperture

in the vertex portion thereof communicating with said cavity for accommodating said switch actuating means, snap-catch protrusions formed on said U-shaped strip on opposing sides of said opening, and a cover plate for said open cavity, said cover plate having a plurality of lead-in conductor accommodation notches cut therein and a resilient strip secured thereto, said strip having two end portions each of which overlaps said plate, said end portions having holes formed therein and being bent in a clamping fashion so that said holes coact with the protrusions on said U-shaped strip as a snap-catch securing means.

5. A switch housing including a half oval-shaped member formed by a pair of half oval-shaped parallel plate portions joined together by a U-shaped strip portion, said portions defining a cavity having an opening thereto, and being sufficiently large to accommodate an electric switch mechanism, and said U-shaped strip portion having an aperture in the vertex portion thereof for accommodating the switch mechanism actuating lever and a snap-catch protrusion formed on the extreme end of the outer face of each of the leg portions thereof, and a flexible rubber covering for said opening, said covering having fastening means formed thereon coacting with said snap-catch protrusions to retain said covering on said housing and to seal the same closed, and a plurality of apertures formed therein and adapted to provide self sealing passages for accommodating the lead-in conductors of the switch contained in the housing.

6. In an electrical switch adapted to be mounted on a flat surface and having a preassembled switch mechanism which has a circular frame therefor with an arcuate portion at the edge of said frame and an actuating member extending radially outwardly from said frame, the combination of a one-piece molded housing member for said switch mechanism having four closed walls and a rectangular opening at one end thereof defined in size and shape by said walls and having at the other end an apertured wall, with the inside surface of said latter wall rounded to provide inside shoulders adapted to receive the arcuate portion of the switch mechanism frame thereagainst to position and support the preassembled switch mechanism within the housing member, with the wall aperture positioned between said shoulders and adapted to receive the switch actuating member extended therethrough, closure means closing the rectangular opening in the housing member and snap fastener means having cooperating portions on said closure means and said housing member to retain the closure means thereon, and switch mounting means for mounting the switch on a flat surface by drawing the one-piece housing member with the switch mechanism therein against such surface and drawing the switch-mechanism frame at its arcuate portion against the inside shoulders within said one-piece housing member.

7. In an electrical switch adapted to be mounted on a flat surface and having a preassembled switch mechanism which has a circular frame therefor with an arcuate portion at the edge of said frame and an actuating member extending radially outwardly from said frame, the combination of a one-piece molded insulating housing member for said switch mechanism having four closed walls and a rectangular opening at one end thereof defined in size and shape by said four walls and having at the other end an apertured wall, with the inside surface of said

latter wall rounded to provide inside shoulders adapted to receive the arcuate portion of the switch mechanism frame thereagainst, with the wall aperture positioned between said shoulders and adapted to receive the switch actuating member extending therethrough, said four walls of said housing member including two side walls with a snap notch in each adjacent the opening, closure means closing the rectangular opening in the housing member comprising an insulating plate supported at the opening, snap fastener means comprising a metal spring clip extending across said insulating plate and having a deformed snap at each end to engage the corresponding snap notches in the housing member and to retain the closure means thereon, and switch mounting means for mounting the switch on a flat surface by drawing the one-piece housing member with the switch mechanism therein against such surface and drawing the switch-mechanism frame at its arcuate portion against the inside shoulders within said one-piece housing member.

8. In an electrical switch adapted to be mounted on a flat surface and having a preassembled switch mechanism which has a circular frame therefor with an arcuate portion at the edge of said frame and an actuating member extending radially outwardly from said frame, the combination of a one-piece molded insulating housing member for said switch mechanism having four closed walls and a rectangular opening at one end thereof defined in size and shape by said four walls and having at the other end an
